US00D831007S

(12) **United States Design Patent** (10) **Patent No.:** **US D831,007 S**
(45) **Date of Patent:** **** Oct. 16, 2018**

(54) **ANTENNA INSULATOR FOR A MOBILE PHONE**

(71) Applicant: **Guang Dong Oppo Mobile Telecommunications Corp., Ltd.**, Dongguan, Guangdong (CN)

(72) Inventor: **Guan Gong**, Guangdong (CN)

(73) Assignee: **Guangdong Oppo Mobile Telecommunications Corp., Ltd.**, Dongguan, Guangdong (CN)

(**) Term: **15 Years**

(21) Appl. No.: **29/560,392**

(22) Filed: **Apr. 6, 2016**

(51) **LOC (11) Cl. 14-03**

(52) **U.S. Cl.**

USPC **D14/230**; D14/250

(57) **CLAIM**

The ornamental design for an antenna insulator for a mobile phone, as shown and described.

DESCRIPTION

FIG. 1 is a lower, front, right perspective view of the first embodiment of an antenna insulator for a mobile phone, showing my new design;

FIG. 2 is a front view thereof;

FIG. 3 is a rear view thereof;

FIG. 4 is a left side view thereof;

FIG. 5 is a partially enlarged view of the top, left side view thereof;

FIG. 6 is a right side view thereof;

FIG. 7 is a top view thereof;

FIG. 8 is the bottom view thereof;

FIG. 9 is a lower, front, right perspective view of the second embodiment of an antenna insulator for a mobile phone, showing my new design;

FIG. 10 is a front view thereof; the rear view being identical to FIG. 3;

FIG. 11 is a left side view thereof;

FIG. 12 is a partially enlarged view of the top, left side view thereof;

FIG. 13 is a right side view thereof;

FIG. 14 is a top view thereof; and,

FIG. 15 is the bottom view thereof.

The broken line in the figure drawings represents unclaimed environment only and forms no part of the claimed design.
